UNITED STATES PATENT OFFICE.

CHARLES THOMAS MILLER, OF MACON, GEORGIA.

FLUSHING-VALVE.

1,251,802.

Specification of Letters Patent.

Patented Jan. 1, 1918.

Application filed February 21, 1916. Serial No. 79,719.

To all whom it may concern:

Be it known that I, CHARLES T. MILLER, a citizen of the United States, residing at Macon, in the county of Bibb and State of Georgia, have invented certain new and useful Improvements in Flushing-Valves, of which the following is a specification, reference being had to the accompanying drawings.

10 This invention relates to certain improvements in flushing valves and it is an object of the invention to provide a novel and improved valve slidably engaged with the outlet pipe of a tank and provided with means whereby a siphon is created upon downward movement being imparted to the valve.

The invention consists in the details of construction and in the combination and arrangement of the several parts of my improved valve whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in elevation and partly in section illustrating a valve constructed in accordance with an embodiment of my invention; and

Fig. 2 is a fragmentary view in perspective illustrating in detail the means coacting with the lever for depressing the valve.

As disclosed in the accompanying drawings, 40 T denotes a tank which may be of any desired configuration and constructed of any suitable material, and 1 denotes a delivery or outlet pipe in communication with the interior of the tank T through the medium 45 thereof and terminating at its inner end a predetermined distance above the bottom of the tank T, and said inner or extended portion of the pipe 1 is surrounded by the sleeve 2 affording a chamber a adapted to contain 50 a sealing medium S, preferably mercury.

3 denotes a vertically movable hollow plunger member telescopically mounted relative to the inner end of the pipe 1 and capable of sliding movement relatively thereto, 55 said member 3 extending within the chamber *a* whereby it will be at once perceived

that the sealing medium S serves to effectively seal the lower or inner end of the tubular member 3 irrespective of its vertical adjustments.

Connected with the member 3 on each side thereof is a siphon leg 6.

4 denotes a lever pivotally supported intermediate its length for rocking movement and having one extremity operatively engaged with the upper end of the member 3, the opposite arm or end portion of the lever 4 having adjustably engaged therewith the poise 5 which serves to normally maintain the connected portions of the member 3 and leg 6 above the water level within the tank T, but it will be perceived that upon the member 3 and leg 6 being forced downwardly, the water will be caused to pass upwardly through the leg 6 and within the member 3, whereby a siphon is created which will result in the requisite discharge of the water from the tank T through the delivery or outlet pipe 1.

Extending through a wall of the tank T 80 and rotatably supported thereby is a shaft 7, the inner portion of the shaft 7 being provided with a rock arm 8 adapted to contact with the arm or end portion of the lever 4, with which the poise 5 coacts, while the outer end of the shaft 7 is provided with an operating member 9. By this arrangement it will be perceived that the requisite rocking movement may be imparted to the lever 4 in order to depress the member 3 and leg 6, and that the shaft 7 will also serve to limit the upward movement of the member 3 and the leg 6 under the influence of the poise 5. 85 90

It is preferred that the lever 4 have an end portion loosely directed through an eye member 10 carried by and extending above the member 3 in order to provide the requisite connection between the lever 4 and said member. 95

It will be noted that when the lever 4 is 100 depressed, that the siphon formed by the arms 3 and 6 will be positively forced down beneath the water to such an extent that about one-half of the water in the tank is assisted in its flow by the action of gravity, 105 thus making a much easier siphonic action. Further, it is to be seen and noted that the outlet pipe is formed practically in two sections, namely, the section 2 and the section 3, the section 2 having double walls forming 110 the sealing cup S and between which double walls the lower end of the section 3 operates.

The section 3 does not touch the double walls of the section 2, but has free movement in the mercury forming the sealing medium between these walls. There is no liability of 5 the siphon striking therefore or becoming jammed, but the siphon will immediately rise after its depression.

From the foregoing description, it is thought to be obvious that a valve constructed 10 in accordance with my invention is of an extremely simple and comparatively inexpensive nature and is particularly well adapted for use by reason of the convenience and facility with which it may be assembled, 15 and it will also be obvious that my invention is susceptible of some change and modification without material departure from the principles and spirit thereof and for this reason I do not wish to be understood as 20 limiting myself to the precise arrangement and formation of the several parts herein shown in carrying out my invention in practice.

I claim:

25 1. A flushing apparatus comprising a tank, a siphon having an inlet leg and an outlet leg, the outlet leg being made in two sections, one section being connected to the tank

and formed with double upwardly extending walls providing a sealing cup, containing 30 liquid sealing material, the other section having sliding engagement in said cup and dipping into said sealing material, and manually actuatable means for positively depressing the inlet leg and the upper section of 35 the outlet leg of the siphon.

2. A flushing apparatus including a tank having an outlet pipe, extending upward within the tank and formed with double walls providing a sealing cup having therein 40 relatively heavy liquid sealing material, a siphon having an outlet leg extending downward between the double walls and into the sealing material and having an inlet leg connected to the upper end of the outlet leg, 45 a lever positively engaged with the siphon whereby the siphon shall move vertically with an oscillation of the lever, means urging the lever to a position where the upper portion of the siphon is above the level of 50 liquid in the tank, and manually operable means for depressing that end of the lever connected to the siphon.

In testimony whereof I hereunto affix my signature.

CHARLES THOMAS MILLER.
